UNITED STATES PATENT OFFICE

JAMES FLOCKHART, OF SAN FRANCISCO, CALIFORNIA

SCREEN PRINTING MACHINE

Application filed December 13, 1930. Serial No. 502,113.

This invention relates to improvements in screen printing machines and more particularly to power driven machines in this class.

Among the objects of the invention are to 5 improve the quality and speed up the production of screen stencil printing machines.

Another object is to simplify the driving mechanism.

A further object is to improve the color 10 applying means.

Other objects and advantages will appear as the description progresses.

In this specification and the accompanying drawings the invention is disclosed in its 15 preferred form. But it is to be understood that it is not limited to this form because it may be embodied in other forms. It is also to be understood that in and by the claims following the description it is desired to 20 cover the invention in whatsoever form it may be embodied.

For further particulars reference is here made to my copending applications as follows: fountain brush, Ser. No. 396,082, filed 25 Sept. 30, 1929; stencil frame, Ser. No. 396,083, filed Sept. 30, 1929; stencil printing machine, Ser. No. 429,337, filed Feb. 18, 1930; sheet gage, Ser. No. 436,502, filed Mar. 17, 1930; 30 stencil printing apparatus, Ser. No. 438,504, filed Mar. 24, 1930.

In the six sheets of drawings:

Fig. 1 is a side elevation of a screen printing machine constructed in accordance with this invention.

Fig. 2 is a plan view from above of the same.

Fig. 3 is a similar view of the power unit for actuating the same.

Figs. 4—5, taken together are an enlarged detail in side elevation of the power transmission means between the actuating cam and the swing frame, taken from the opposite side to that shown in Fig. 1.

Fig. 6 is a detail front view of the clutch mechanism.

Fig. 7 is a side view of the same.

Fig. 8 is an enlarged detail in side elevation, partially in vertical section, of the pivotal mounting of the swing frame.

Fig. 9 is a plan view from above of the same.

Fig. 10 is an enlarged fragmentary detail end view of one side of the ink fountain crosshead guide. 55

Fig. 11 is a cross section of the same.

Fig. 12 is an enlarged detail view in vertical section diagrammatically illustrating the ink fount in the open operative and spreading position. 60

Fig. 13 is a similar view of the same in the closed, return, scraping position.

Fig. 14 is a plan view of the same combined with its guiding and operating assembly.

In detail the construction illustrated in 65 the drawings referring to Fig. 1, comprises the main frame, preferably of cast iron, having two side members 1—1, suitably cross braced to form a substantial support for the operative mechanisms. The operating table 70 or platen 2, extends across the top of the main frame at the front, and is securely bolted thereto. This platen may be composed of the conventional laminated wood panel, to which paper registering guides may be thumb 75 tacked, or it may be of any other non-warping material suitable for the purpose.

The pillow bearings 3—3 are fixed on opposite sides of the top rails 4—4 of the main frame. The eccentric blocks 5—5 are revolute in the bearings 3, and held in adjusted 80 position by the set screws 6—6 respectively. The pivot shaft 7 has its opposite ends fixed in the blocks 5—5 so that it may be adjusted vertically with respect to the plane of the platen 2, by turning the eccentric blocks 5—5. The blocks are rotated by the handles 8—8 85 respectively fixed in their protruding ends, see Fig. 9.

The swing frame has two relatively wide 90 side bars 9—9 cross connected by the front and rear transverse bars 10—10, to form a rigid rectangular frame, see Figs. 1—2. The pivot shaft 7, passes through the ends of the side bars 9—9 which have the extensions 95 11—11 extending beneath the set screws 12—12. These set screws are threaded in the brackets 13—13 on the pillow bearings 3—3, see Figs. 8—9. By adjusting the screws 12—12 the plane of the swing frame when 100

in operative position can be brought parallel with the plane of the platen 2, after the height of the swing frame has been determined by adjusting the eccentrics 5—5.

5 The overhanging weight of the swing frame is counter-balanced by the counter weight 14 adjustable on the extension rods 15—15 which are fixed in and extend rearwardly from the end bar 11, see Figs. 1—2.

10 The guide slots 16—16 are milled in the inner faces of the side bars 9—9 to receive the crosshead guides 17—17 on the opposite ends of the crosshead 18, extending across the width of the swing frame. The opposite ends of the crosshead guides are split as at 19—19 so that they may be spread by the screws 20—20 so that they will exert a frictional resistance within the slots 19—19, for reasons which will hereinafter appear.

15 20 The brackets 21—21 are a part of the crosshead guides and are slotted at 22—22 to receive the opposite ends of the transverse push rod 23 held therein by set screws. (See Figs. 10—11.)

25 20 The brackets 24—24 are fixed on the crosshead bar 18 by the setscrews 25—25. These brackets are cross-connected by the transverse fount pivot rod 26, passing through and fixed in the upward extensions 27—27 of the 30 brackets. (See Figs. 2—12—14.)

The ink fount comprises the rear plate 28 having the lugs 29—29 pivoted on the rod 26. This plate 28 is slotted in its lower edge to receive the spreader 30. The opposed plate 31 has the sides 32—32 engaging the edges of the plate 28 and also pivoted on the rod 26. The lug 33 formed on the lower portion of the plate 31 is slotted to receive the spreader 34. The space between the plates 28 and 31 forms a fount to hold the desired ink X or any of the conventional color enamels used in screen printing. The sides 32—32 have the hooks 35—35 formed thereon and engaging the push rod 23. (See Figs. 12—13.)

45 40 When the rod 23 is pushed forward, as shown in Fig. 12, the hooks 35—35 push the plate 31 away from the plate 28 and open the fount at 36, permitting the ink X to flow downward upon the screen stencil 37, across 50 the surface of which it is spread by the spreader 30. The exact quantity of ink necessary to the required screen area is regulated by the adjusting screw 38 threaded in the plate 31 and bearing against the plate 28. The retarding action due to the friction 55 between the spreader 30 against the screen 37 holds the plate 28 and transfers the thrust of the rod 23 to the plate 31, thus making the fount positive opening at 36.

60 60 On the reverse or back stroke the pull of the rod 23, engaging the hooks 35—35, pulls the plate 31 against the plate 28, closing the opening at 36 and stopping the ink flow. This brings the plate 28 against the crosshead 65 18. The radius from the pivot 26 lifts the

spreader 30 above contact with the screen 37 and swings the spreader 34 into contact therewith, which also forces the ink through the stencil and scrapes any excess ink from the screen 37, to be redistributed on the 70 next stroke of the fount.

The slots 22—22 on the brackets 21—21, cause the push rod 23 to actuate the fount, as described, before the crosshead 18 is moved. To insure this synchronous action it is necessary to hold the crossheads 17—17 in the guides 16—16, until the rod 23 takes up the lost motion provided in the slots 22—22. This retardation is accomplished by spreading the slotted ends of the crossheads by means of the screws 20—20.

The push rod 23 is actuated by the power mechanism as shown in Figs. 1—3—5—6—7. Referring to Fig. 3, the motor 38 mounted on the floor 1' of the main frame, is belted at 39 to the shaft 40 of the reduction gear 41. The conventional motor R. P. M. of 1700 is reduced about 50 to 1 in the reduction gear. Attention is directed to the fact that all the printing operations are actuated at relatively low speed, by the novel combination of mechanical movements employed. The advantage of slow speed clutching, declutching, reciprocating and other movements is obvious.

The power from the reduction gear shaft 42 is transmitted through a clutch to the cam shaft 43, journaled in the bearings 44—44 fixed to the floor 1'. The cam 45 is fixed on this shaft between these bearings. (See Figs. 3—5.) This cam has the contour groove 46 formed in its face, which controls the raising and lowering of the swing frame and the reciprocations of the ink fount.

The countershaft 47 is journaled in the bearings 48—48 fixed to the floor 1'. The pinion 49 and the sprocket 50 are fixed on the countershaft 47. The rack 51 has teeth enmeshed with the teeth of the pinion 49, and the head 52, slideable in the guide 53 fixed to the floor 1'. The antifriction roller 54 is mounted on the side of the rack 51 and engages the contour groove 46 of the cam. The rack is reciprocated by the rotation of the cam 45.

The reciprocation of the rack oscillates the shaft 47, which is transmitted through the sprocket chain 55, to the sprocket 56 fixed on the shaft 57, which extends across the width of the frame 1, and is suitably journaled in the bearings 58—58 mounted on the top rails 4—4.

There are two pinions 59—59 fixed on the shaft 57, which are enmeshed with the racks 60—60. The racks are guided in the saddles 61—61, pivoted on the shaft 57. (See Fig. 4.) These racks are joined at 62—62, to the extensions 63—63 which pivotally engage the opposite ends of the push rod 23. (See Figs. 1—10.)

Through the drive mechanism just described the reciprocations of the rack 51 are 130

transmitted to the racks 60-60 to push and pull the rod 23. In Fig. 1, the rod 23 has completed the forward stroke with the ink fount open is described and shown in Fig. 12. The 5 return stroke will close the fount as shown in Fig. 13. The completion of the return stroke will bring the cross head guides 17-17 to the ends of the guides 16-16 where they will stop, so that the last portion of the pull 10 of the rod 23 will swing the swing frame upward on its pivot 7 into the position indicated in dotted lines in Fig. 1.

During the interval that the swing frame is up, the operator removes the printed impression sheet from the platen 2 and substitutes 15 a blank sheet.

The first part of the next forward thrust of the rod 23 will lower the swing frame to the platen, open the fount and push it forward across the stencil screen 37, as shown in Fig. 1, ready to repeat the operations of automatically printing through the screen 37, as previously described.

The clutch mechanism interposed between 25 the reduction gear 41 and the cam shaft 43, is best disclosed in Figs. 1-3-6-7. Referring to Fig. 6, the disc 64 is fixed on the end of the shaft 42. The clutch pins 65-65 are slidable in this disc and are held extended 30 by the springs 66-66 fixed to the rear face of the disc at 67 and have their free ends entered in holes through the pins 65-65.

A similar disc 68 has its hub 69 slidably splined on the end of the shaft 43 and is provided with the holes 70-70 which are adapted to register with the pins 65-65.

The clutch lever 71 is pivoted on the shaft 72 pivoted in the bearings 73-73, fixed on the floor 1'. The upper end of the clutch 40 lever is forked and slotted to receive the trunnions 75-75 on the yoke 76 engaging the annular groove 77 in the hub 69. The lower extension of the clutch lever is in the form of an inverted Y to form the treadles 78-79, for 45 the right and left feet of the operator respectively.

When the operator depresses the treadle 78 with his left foot, the disc 68 slides back on its spline and disengages from the pins 65-65, 50 disconnecting the prime mover from the printing mechanism. Contrawise, when the treadle 79 is depressed the disc 68 approaches the disc 64, the ends of the spring pressed pins 65 riding the face of the disc 68 until 55 they drop into the holes 70, as shown in Fig. 6.

It is important that the power be declutched at a definite point in the operation of the swing frame; for instance, when the swing frame is in the elevated position, see dotted lines in Fig. 1. This is automatically accomplished by the trigger 80 pivoted on the shaft 72 with its inclined end 81 in the path of the trip 82, fixed on the shaft 43. The machine is stopped by the operator removing both feet 60 from the treadles 78-79. The trip 82 then

slides down the incline end 81 and forces the trigger 80 outward against the tension of the spring 83 which pulls the clutch lever 71 with it and withdraws the disc 68 from engagement with the clutch pins 65-65. This stops 70 the swing frame in a position of its operation determined by the adjusted position of the trip 82. The treadle 78 is only used in emergencies where it is desirable to declutch regardless of other conditions.

The speed of the machine is to be timed with regard to the ability of a skilled operator to feed it, without declutching for each cycle of operation. A skilled feeder will keep his foot 75 on the treadle 79 for continuous operation, in which case the trip 82 will merely snap past the trigger 80, without declutching the power shaft 42.

The platen 2 is inclined downward from the operator to facilitate the feeding operation. The inclined platen has the further mechanical advantage that driving the spreader 30, 80 up the incline, increases its friction against the screen 37, the function of which has been previously described. Pushing the flowing ink X against gravity also improves the uniformity of its spread. The inclined platen gives the operator a better view of the printing field of the platen altho the arc of the swing of the swing frame is lessened several degrees, with its obvious mechanical economies and other advantages.

The contour 46 of the cam is plotted to initiate the raising and lowering operation of the swing frame at relatively slow speed, 100 while the reciprocation of the fount back and forth is speeded up to the maximum that proper ink distribution will permit.

A multiplicity of founts can be strung upon the pivot rod 26, to simultaneously feed several colors of ink to the screen 37, if desired. When the ink fount is removed, the screw 38 is turned until the opening 36 is clamped tight and the lugs 29-29 bear against the lugs 29'-29' on the sides 32-32, then the rod 26 105 is withdrawn laterally, and the hooks 35-35 lifted off the push rod 23. When not in use the ink founts will stand upright on the two spreaders 30-34.

The frame 84 of the screen 37 is adjustably supported within the swing frame by the adjusting screws 85-85 which are threaded through the members 9-9-10-10 of the swing frame.

The spreaders 30-34 are preferably composed of leather and are set at about sixty degrees to the plane of the screen 37. This angle gives a brushing or spreading effect as distinguished from the harsh scraping action of the squeegees heretofore used in this art. This more gentle distributing action of the spreaders 30-34, forces the ink gently through the screen, with improved textural effects on the print rather than to mash the screen down upon the impression surface and 120 125 130

lift the ink as occurs with a heavily pressed squeegee as heretofore.

In addition to the counter weight 14, the swing frame is provided with buffer springs, to cushion its rise and fall at the ends of the strokes of the reciprocating mechanism. Referring to Figs. 1-2, the collars 86-86 on the rods 15-15, anchor the transverse bar 87. A parallel transverse bar 88 is fixed across

10 the main frame 1.

The sleeve 89 is pivoted on the bar 87 and has the stem 90 slidably through a hole in the bar 88. The adjustable collars 91-92 are fixed on the stem by the setscrews 93-94 respectively. The expansion springs 95-96 encircle the stem 90 between these adjustable collars and the bar 88.

Lowering the swing frame 9 compresses the spring 95, and raising the swing frame compresses the spring 96. These springs thus resiliently arrest the momentum of the swing frame, to prevent it banging down onto the platen 2 and possibly breaking the brackets 11-11, on the down stroke or rising too high 25 on the up stroke.

Having thus described this invention, what I claim and desire to secure by Letters Patent is:

1. A screen printing machine including a main frame; a platen; a swing frame pivoted on said main frame and adapted to carry a stencil above said platen; inking means guided on said swing frame; rack and pinion means engaging said inking means adapted to raise and lower said serving frame; and a power driven cam means operatively engaging said rack and pinion means.

2. A screen printing machine including a main frame; an inclined platen; a swing frame pivoted to said main frame and adapted to carry a stencil above said platen; inking means guided on said swing frame; a pinion on said main frame; a rack enmeshed with said pinion and pivoted to inking means and adapted to raise and lower said swing frame; and means for rotating said pinion.

3. A screen printing machine including a main frame; a platen; a swing frame pivoted to said main frame and adapted to carry a stencil above said platen; reciprocating means synchronously engaging said swing frame and inking means; and motor means geared to said reciprocating means.

4. A screen printing machine including a main frame; a platen; a swing frame pivoted to said main frame and adapted to carry a stencil above said platen; a crosshead guided in said swing frame; an inking means pivoted on said crosshead; a push rod engaging a slot in said crosshead and said inking means; reciprocating means engaging said rod; and power means for continuously operating said reciprocating means.

5. A screen printing machine including a main frame; a platen; a swing frame pivot-

ed to said main frame and adapted to carry a stencil above said platen; a crosshead guided in said swing frame; an inking means on said crosshead; reciprocating means engaging said crosshead for synchronously raising and lowering said swing frame, moving said crosshead and opening and closing said inking means on the forward and reverse strokes of said crosshead, respectively.

6. A screen printing machine including a main frame; a platen; a swing frame pivoted to said main frame and adapted to carry a stencil above said platen; an inking means movable on said swing frame; reciprocating means for synchronously raising and lowering said swing frame, and moving, opening and closing said inking means on the forward and reverse strokes of said reciprocating means; and a power operated means for actuating said reciprocating means.

7. A screen printing machine including a main frame; a platen; a screen frame movable on said main frame and adapted to carry a stencil above said platen; inking means cooperating with said stencil; a power actuated cam on said main frame; a rack and pinion unit actuated by said cam; a second rack and pinion unit operatively engaging said inking means adapted to raise and lower said screen frame; and transmission means between said rack and pinion units.

8. A screen printing machine including a main frame; a platen; a screen frame movable on said main frame and adapted to carry a stencil above said platen; inking means cooperating with said stencil; power operated means for automatically actuating said movable frame and inking means in synchronism; and clutch means adapted to apply the power at a predetermined point in the cycle of said automatic actuating means.

9. A screen printing machine including a main frame; a platen; a screen frame movable with respect to said platen; inking means on said movable frame; power actuated shaft for automatically moving said movable frame and actuating said inking means in synchronism; and a clutch interposed in said shaft; a clutch operating lever; a trip on said shaft; a trigger in the path of said trip resiliently connected to said lever, said trip being set on said shaft with respect to the operating cycle of said movable frame and inking means.

10. A screen printing machine including a main frame; a platen; a swing frame pivoted on said main frame and adapted to carry a stencil above said platen; reciprocating means for raising and lowering said swing frame; and means between said main frame and swing frame adapted to be tensioned as said swing frame descends to resiliently arrest the movement of said swing frame.

11. A screen printing machine including a main frame; a platen mounted on said

frame; a swing frame pivoted to said main frame and adapted to carry a stencil above said platen; a crosshead having guides frictionally slidable in said swing frame; inking means on said crosshead; reciprocating means engaging said crosshead for raising and lowering said swing frame and sliding said crosshead.

12. A screen printing machine including
10 a main frame; a platen mounted on said frame; a screen frame movable with respect to said platen; inking means on said movable frame; reciprocating means for moving said movable frame and actuating said inking
15 means; a prime mover for driving said reciprocating means; a clutch interposed between said driving and reciprocating means; a lever for operating said clutch, pedals connected to said operating lever for engaging
20 and disengaging said clutch, means resiliently connected to said operating lever and adapted to disengage said clutch at a pre-determined point in the cycle of operation of the machine.

25 In testimony whereof I have hereunto set
my hand this 5th day of December, 1930.

JAMES FLOCKHART.
